UNITED STATES PATENT OFFICE.

ANDREW CHRISTIANSON, OF BUTLER, PENNSYLVANIA, ASSIGNOR TO STANDARD STEEL CAR COMPANY, OF PITTSBURGH, PENNSYLVANIA, A CORPORATION OF PENNSYLVANIA.

BRAKE-BEAM.

1,235,553.

Specification of Letters Patent.

Patented Aug. 7, 1917.

Application filed July 25, 1916. Serial No. 111,160.

To all whom it may concern:

Be it known that I, ANDREW CHRISTIANSON, a citizen of the United States, and resident of Butler, in the county of Butler and 5 State of Pennsylvania, have invented a new and useful Improvement in Brake-Beams; and I do hereby declare the following to be a full, clear, and exact description thereof.

My invention relates to brake-beams, one 10 object being to provide a brake-beam where the brake-heads secured thereto may be of simple form, and if desired, forged of wrought metal; and another object being to provide a wrought metal, brake-beam strut 15 and lever fulcrum between the compression and tension members. The invention is especially applicable in connection with the brake-beams made of wing bars of the type known as the Davis brake-beam. The invention 20 also involves the formation of the brake-beam member itself.

To these ends, it consists of the combination of a wing-bar member having a compression member and one rib sheared longitudinally from the bar between its ends to form a tension member, and the integral end portions of the bar forged down to substantially solid section, and brake-heads secured to such solid end portions. It also 25 comprises the formation of the brake-beam member itself. It also comprises a brake-beam strut formed of two strips engaging the compression member and lapping around the tension member and twisted a 30 quarter turn to form the brake-lever fulcrum, said strips being riveted together.

In the accompanying drawing, Figure 1 is a view of the invention, one brake-head being removed from the brake-beam; Fig. 2 35 is an edge view of the brake-beam, Fig. 3 is a cross section on the line 3—3, Fig. 1; Fig. 4 is a side or edge view of the brake-beam; and Fig. 5 is a cross section of the 40 rolled bar.

The brake-beam member or body 2 is 45 formed of a wing-bar rolled section, being of the section known as the Davis brake-beam, where three, 3, 4 and 5, of the wings are rectangular, while the fourth wing 6 is bulbous, so that when sheared from the other wings at 6^a, as illustrated in dotted lines Fig. 5, it is round in cross section. In forming the brake-beam, this wing-bar 50 is sheared longitudinally between the ends

forming the compression member 16 composed of the wings 3, 4 and 5, and the round tension member 6 so formed is separate from the compression member. The ends of the bar remain integral as at 7; and the ends of this bar are then reheated 60 and forged to solid section as at 8, preferably to round section, this being the preferred form for receiving the brake-heads 10 which brake-heads are thus made of simple form having the sockets 11 fitting over 65 the solid end portions 8 of the brake-beam body. Such a section can be easily forged and finished so that the whole brake-beam can be made of forged metal. The brake-heads 10 can be held in place by suitable 70 bolts 12 passing through the solid ends 8 and secured in place by pins 13, and also by washers 14 secured in place by the cotter pins 15.

The brake-beam strut 17 can also be 75 made of wrought metal and of simple form, being formed of two straps 18, 19 with the hooked end portions 20 conforming in shape to and engaging the T-shaped compression member 16 of the brake-beam body, and 80 lapping around the circular tension member 6 of said body, and then twisted as at 21, and again lapped as at 22, 23 to form the brake-lever fulcrum 24, having the hole 25 at the end thereof. These two straps 18 85 and 19 are secured in place by rivets, as at 26 and 27, and in the twisted portions at 28. Thus I am enabled to provide a brake-beam which may be composed entirely of 90 wrought metal, decreasing the weight thereof, and increasing its strength. I also provide a simple, strong connection between the ends of the brake-beam member and the brake-heads, doing away with the complicated shaped socket corresponding in shape 95 to the wing-bar connecting the brake-heads and brake-beam members, as heretofore employed.

What I claim is:

1. The combination of a brake-beam 100 formed of a wing-member, having a compression member, and one rib sheared longitudinally therefrom between the ends to form the tension member and the integral end portions forged down to substantially solid section, and brake-heads secured to 105 said solid end portions.

2. The combination of a brake-beam

- formed of a wing member, having a compression member, and one rib sheared longitudinally therefrom between the ends to form the tension member and the integral 5 end portions forged down to substantially round section, and brake-heads secured to said round end portions.
3. The combination of a brake-beam having a compression member and a tension 10 member, and a brake-beam strut formed of two straps engaging the compression member and lapping around the tension member, and twisted a quarter turn to form the brake-beam fulcrum, said straps being riveted together.
4. The combination of a brake-beam having its compression member of T-shaped section and its tension member of round section, and a brake-beam strut formed of 15 two straps having hooks engaging the T-

shaped tension member and lapping around the tension member, and twisted to form a brake-lever fulcrum, said straps being riveted together.

5. The method of forming a brake-beam 25 member, consisting in rolling a wing-bar, shearing the same longitudinally between the ends to form a T-shaped compression member and a separate tension member, and reheating the integral end portions of said 30 bar and forging the same down to substantially solid section to receive the brake-heads.

In testimony whereof, I the said ANDREW CHRISTIANSON have hereunto set my hand.

ANDREW CHRISTIANSON.
